Primary Examiner — Rhea Shields

(74) Attorney, Agent, or Firm — Charles S. Sara; DeWitt Ross & Stevens, S.C.

(57) **CLAIM**

The ornamental design for a portable food and beverage container, as shown and described.

DESCRIPTION

FIG. 1 is a front perspective view of the portable food and beverage container showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is an alternative front perspective view thereof.

In the drawings, the broken lines are for the purpose of illustrating environment only and form no part of the claimed design.

1 Claim, 5 Drawing Sheets
